UNITED STATES PATENT OFFICE

FREDERICK W. NEBHUT, OF CLEVELAND, OHIO; M. FRANCES NEBHUT ADMINISTRATRIX
OF SAID FREDERICK W. NEBHUT, DECEASED

FASTENER FOR FABRICS

Application filed April 25, 1925. Serial No. 25,784.

The present invention relates to a fastener for fabrics, and particularly to a continuous seam fastening means which may be operated to open or close a seam or juncture in a single 5 operation, and which when closed will maintain the edges of the cloth in engagement throughout their entire length. A further object of the invention is the provision of fastening means of this character which shall 10 be inexpensive in construction, easy and convenient to apply to the edges of the fabric to be secured and extremely strong and reliable in use. To the accomplishment of the foregoing and related ends, said invention, 15 then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Fig. 1 is a plan view of my improved fastening means secured to adjacent edges of strips of fabric; Fig. 2 is a transverse section of the same on the line 2—2, Fig. 1; Fig. 3 is a similar view on the line 3—3 of Fig. 1; Fig. 4 is a similar view on the line 4—4 of Fig. 1; Fig. 5 is a plan view of one of the fastening channels showing its method of attachment to a strip of metal; Fig. 6 is a plan view of the guide or needle member of the 35 fastening means; Fig. 7 is a section on the line 7—7 of Fig. 6; Fig. 8 is a plan view showing another means of securing the channel member to the fabric; Fig. 9 is a transverse section illustrating the action of the fastening 40 means when tension is applied to pull apart the adjacent edges of the strip; Fig. 10 is a view in perspective of a modified form of the fastening means; Fig. 11 is a plan view illustrating still another modification of fastening means; Fig. 12 is a plan view showing a continuous threading cord for operating the fastening means; and Fig. 13 is a view in perspective of a sheet metal channel member.

Various types of continuous fastening ele-

ments or means for detachably joining the edges of fabric in clothes, covers for various articles, overshoes and the like, have been from time to time suggested and several different types have been put into actual use. 55 So far as I am aware all of these constructions require such accuracy of mounting on the edges of the fabric and such perfect alignment of the individual fastening elements that they cause considerable trouble in 60 use unless operated with great care and prevented from becoming dirty or rusty, as is of course the constant tendency where the fastening means are on outer garments or are subjected to the atmosphere. The purpose of 65 the present invention is to provide a simple and inexpensive continuous fastening means which will not be subject to the above objections and which will not require closely accurate workmanship or perfect alignment of 70 parts to insure its continuous perfect operation.

In Fig. 1 I have shown two strips of fabric 1 and 2, the adjacent edges of which are desired to be joined. The strips are provided 75 with hems 3 and 4, respectively, to reinforce the edges. The hem 3 also serves to receive and position a fastening or locking member 5, preferably in the form of a flexible cord or the like, provided with a guide or needle 6 80 which serves to thread the cord through this hem and into the channel members now to be described. In the other hem 4 is disposed a flexible metal strip 7, to which are secured a series of relatively short sockets or open 85 channel members 8, the form of which is best shown in Figs. 3, 4, 5 and 9, and which are secured to the plate 7 by any suitable means, such as by a drop of solder 10 on each of the ends 9 of the sockets, as shown in Fig. 5. 90

The socket or open channel members 8 referred to above may be made from a single piece of wire having its intermediate portion forming one of the terminal attaching ends 9 and the other two ends of the wire 95 twisted together as illustrated in Figure 5 and forming the other terminal end portion, or if desired, these members 8 may be made of two pieces of wire having their ends similarly twisted together. If desired the metal 100

strip may, under certain conditions, be eliminated, in which case the channel members are provided with eyes 11 which are then sewed to the hem 4, as shown in Fig. 8. Similarly, 5 a sheet metal channel 13 may be employed if desired, such a channel being shown in Fig. 13, and consisting of a flat folded portion 14 provided with retaining ears 15 stamped up from the body of the sheet and with oppositely arranged jaws or channels 16 and 17. The lugs 15 are pressed through the fabric and then bent down to retain the channel in place, and of course, if desired, other fastening means may equally well be employed. Each 10 of the members 8 consist of a single piece of wire joined together at their ends, bent to provide aligned spaced sockets 50 having at one side of each end integral attaching means 51 and at the other side of said ends restricted 15 openings 52. Extending between each of such socket portions and at the points of the restricted openings are connecting pieces 53 the latter providing with openings 52 an elongated restricted opening 54.

20 The guide or needle 6 consists of a circular portion 70 which is hollow, and within which its clamped the end of the cord or other flexible member 5, while there extends laterally from this cylindrical portion 70 a flat guiding 25 vane 18 which is provided with a sharpened end portion 19, and to which is secured an operating cord 20. This guide is disposed within the hem 3 and the width of the vane at its wide portion substantially fills the 30 width of the hem so that as the guide is drawn through the hem 3 the cylindrical portion 70 is pressed against the outer edge of the hem and the cord 5 is drawn along at this portion of the hem. A pull on the cord 20 35 tends to rotate the guide slightly in a counter clockwise direction (looking at Figs. 1 and 6), and thus tends to throw the sharpened end 19 against the outer extremity of the hem and into and between the channel members 40 as will now be explained.

45 The various socket members are first secured to the hem 4 in equidistant relation and at corresponding points on the hem so that these sockets or channels normally lie in the same plane and the openings in the channel members are in alignment. The fastening member, that is, the cord 5, with its head or guide, is now inserted in the other hem 3 and the hems are brought together and the 50 fastening cord is started through the first of the channels 8 and when so positioned the hem 3 is closed at that end of the strip in order to prevent accidental removal of the guide. The operating cord 20 is also disposed within the hem 3 and extends from the 55 other end of this hem. By pulling on this cord the guide 6 and cord 5 are drawn successively through the adjacent channels 8, the end 19 of the guide being moved into successive channels and thus acting to thread

the cord 5 within these various elements. This action of the guide also initially brings the flat hem between the channels 8 and this hem is then distended and pressed into engagement with the channels by the circular fastening cord 5 as it is drawn therethrough by the guide. 70

The locking action is secured by the fact that the fastening element 5 is of sufficient diameter so that it will not pass through the opening 22 in the channels 8. The harder the two edges are drawn away from each other the tighter will the fastening element 5 press the hem against the sides of the channels 8, and as these channels extend from end to end of the two fabrics the combined strength of the joint which is secured in this way is very considerable, and it is practically impossible under ordinary conditions to spring the channels 8 sufficiently apart to permit of the lateral withdrawal of the other hem and the fastening element from between them. Even if under some extraordinary tension one or more of the channels are opened the fastening element and hem 3 can be replaced with 90 in these channels and the channels can then be closed by springing the metal down into its original position either by hand or by suitable tools if found necessary. 95

In order to open the joint between the 95 fabrics it is only necessary to reverse the operation and to pull the fastening member 5, which, at its upper end is provided with a ring 23 to retract the guide and the fastening element through whatever portion of the 100 seam it is desired to open.

If desired the seams may be sewed or otherwise secured together at the upper end, such as the point 24 (see Fig. 1), or the two strips may be entirely disconnected and may 105 be provided with suitable fastening means in the form of a hook 25 and eyelet 26 (see Fig. 11), which, when secured together will bring the hems into such relation that with a little care the guide may be started through the 110 first of the channels 8, after which it will guide itself through the other channels and will act as already described to secure the hems on the fabrics together. 115

In Fig. 12 I have shown a continuous and 115 combined fastening element and operating cord. The fastening element consists of a cylindrical cord 27 of the form already described and is provided with a guide or needle 28, to which is secured an operating cord 120 29, on which is loosely mounted a handle or ring 30. The handle or ring always hangs below the lower edge of the strip of fabric, and by pulling on this handle the cord 29 is pulled down and the fastening means are 125 operated. The cord, instead of hanging loosely from the end of the hem 3 is returned within this hem and is passed around a rivet 31 and is then again secured to the fastening element at the point 32. This construction 130

affords a more sightly operating means, but it is necessary in operating it to sometimes pull directly on the cord 29 instead of on the ring 30, while to unfasten the same the 5 fastening member 27 is pulled upward as in the previous construction.

In Fig. 10 I have shown a modification of the fastening means in which the channels or socket members 35 are formed as a part 10 of a single strip of metal which is secured to the edge 36 of a strip of fabric. The other strip 37 is provided with a hem 38, within which is disposed a locking strip or flexible element 39 which, when drawn through the 15 hem, threads its way into the successive sockets of the strip 35 and is of such a size that it snubs the hem against the edges of the socket 35 in the manner previously described.

This snubbing action is illustrated in Fig. 20 9, in which the two hems are shown when placed under a tension, which tends to pull them apart. The hem 3 is pulled toward the opening in the channel 8, but is prevented from removal by the diameter of the fastening element 5, which, however, has sprung or 25 distorted the sides of the channel from the dotted position to the full line position shown in this figure.

The advantages of the present construction 30 are its simplicity and economy, and the flexibility which is given to the same by reason of the large number of individual and relatively short channels or sockets.

Other modes of applying the principle of 35 my invention may be employed instead of the one explained, change being made as regards the mechanism herein disclosed, provided the means stated by any of the following claims or the equivalent of such stated 40 means be employed.

I therefore particularly point out and distinctly claim as my invention:—

1. Fastening means for fabrics comprising 45 two strips of fabric having adjacently disposed edges and one of said strips having a hem formed along its edge, a series of separate resilient channel members secured in alignment along the edge of said other strip, each of said members having an opening on 50 the side adjacent said other strip, and a flexible fastening element disposed in said hem, said element having a guide secured to one end thereof, said guide filling said hem and having a flattened portion adapted upon longitudinal movement thereof through said 55 hem to enter the lateral openings in said channels and to draw said flexible member endwise into said channels, said flexible member locking said hem within said channels and being formed to prevent lateral displacement through the opening therein.

2. A fastening means for fabric having a 60 hem along its edge, comprising a flexible fastening member and a metallic guide secured to one end thereof, said fastening member and

guide being movable longitudinally within said hem.

3. Fastening means for two strips of fabric having adjacently disposed edges and one of said strips having a hem formed along its 70 edge, comprising a flexible fastening element adapted to move longitudinally within said hem, a metallic guide secured to one end of said element, and means provided on the edge of the other of said strips adapted to co-operatively engage with said fastening element 75 to detachably secure said fabric strips together.

4. Fastening means for two strips of fabric having adjacently disposed edges and one of 80 said strips having a hem formed along its edge, comprising a flexible fastening element adapted to move longitudinally within said hem, a metallic guide secured to one end of said element, means provided on the edge of 85 the other of said strips adapted to co-operatively engage with said fastening element to detachably secure said fabric strips together, and means for moving said fastening element within said hem. 90

5. Fastening means for two strips of fabric having adjacently disposed edges and one of said strips having a hem formed along its edge, comprising a flexible fastening element adapted to move longitudinally within said 95 hem, a metallic guide secured to one end of said elements, means provided on the edge of the other of said strips adapted to co-operatively engage with said fastening element to detachably receive said fabric strips together, and means attached to said guide for moving 100 said fastening element into engagement with said first-named means. 105

6. Fastening means for two strips of fabric having adjacently disposed edges and one of 110 said strips having a hem formed along its edge, comprising a flexible fastening element adapted to move longitudinally within said hem, a metallic guide secured to one end of said elements, means provided on the edge of 115 the other of said strips adapted to co-operatively engage with said fastening element to detachably receive said fabric strips together, means attached to said guide for moving said fastening element into engagement with said first-named means, and means attached to the other end of said element for moving the same from fastening position.

Signed by me this 18th day of April, 1925.

FREDERICK W. NEBHUT.
